UNITED STATES PATENT OFFICE

100,695

DESIGN FOR AN AIRPLANE

Taft Harris, Portland, Oreg.

Application December 14, 1935, Serial No. 60,061

Term of patent 3½ years

To all whom it may concern:

Be it known that I, Taft Harris, a citizen of the United States, residing at Portland, in the county of Multnomah and State of Oregon, have invented a new, original, and ornamental Design for an Airplane, of which the following is a specification, reference being had to the accompanying drawings, forming part thereof.

Figure 1 is a top plan view of an airplane, showing my new design.

Figure 2 is a view in side elevation thereof.

Figure 3 is a front elevational view.

I claim:—

The ornamental design for an airplane as shown.

TAFT HARRIS.
